UNITED STATES PATENT OFFICE.

FRED C. OLIN, OF BUFFALO, NEW YORK.

SPIKE-FORMING MACHINE.

Application filed January 2, 1925. Serial No. 36.

This invention relates to a machine for forming spikes such as are commonly employed for securing the rails of railways upon wooden ties, and more particularly to a machine which operates upon the shanks of such spikes so as to produce longitudinal grooves in the sides thereof whereby a greater holding effect is obtained of the spike on the tie into which it is driven, and also to a machine which will produce a comparatively sharp point upon the front or lower end of the spike after the grooving operation has been performed, which point permits of driving the spike in easily into the tie, and also enters the latter without unduly cutting or crushing the fibers of the same, thereby obtaining the maximum holding effect of the spike for fastening the rail to the tie.

It is the object of this invention to produce a machine whereby the operations of grooving and pointing the shank of the spikes may be effected economically, effectively and expeditiously by means which are strong and durable and not liable to get out of order and necessitate the employment of a minimum amount of manual labor, thereby enabling such spikes to be produced at comparatively low cost.

In the accompanying drawings, Figure 1 is a side elevation, partly in section, of a spike forming machine embodying my invention. Figure 2 is a fragmentary top plan view, partly in section, of the means whereby the spike blanks are transferred successively from the spike supplying device to the spike forming mechanism. Figure 3 is a vertical cross section, on an enlarged scale, taken on line 3—3, Figure 1. Figure 4 is a front elevation of the machine. Figure 5 is a side elevation of one of the spike blanks before the same has been operated upon by my improved forming machine. Figure 6 is a cross section taken on line 6—6, Figure 5. Figure 7 is a side elevation of a spike showing the shape of the same after it has been operated upon by my improved forming machine for producing longitudinal grooves in the side thereof, and a point at the front end thereof. Figure 8 is a fragmentary longitudinal section of a part of the spike showing the contour of the bottom of the groove which is formed in the side of the spike. Figure 9 is a cross section, on an enlarged scale, taken on line 9—9, Figure 7. Figure 10 is a side elevation of the preferred form of die employed in this machine for producing a longitudinal corrugated groove in the side of the spike and an inclined or tapered face on the front end thereof. Figure 11 is a front elevation of this die. Figure 12 is a fragmentary vertical longitudinal section on an enlarged scale, showing parts of the means whereby the spike blanks are supplied and the means whereby these spike blanks are taken from the supplying means and presented to the forming mechanism. Figure 13 is a side elevation of part of the spike transfer mechanism shown in a position different than that indicated in Figure 12. Figure 14 is a fragmentary top plan view, partly in section, of the spike supplying mechanism. Figure 15 is a fragmentary side elevation of the cooperating parts of the spike supplying mechanism and the spike transferring mechanism. Figure 16 is a fragmentary, vertical, longitudinal section, on an enlarged scale, showing one of the units of the forming mechanism whereby one of the longitudinal sides of the spike is operated upon for producing a longitudinal groove therein, and a point at the lower or front end thereof. Figure 17 is a horizontal section of the same taken approximately on line 17—17, Figure 16. Figure 18 is a fragmentary top plan view of the adjacent parts of the spike supplying mechanism and the spike transfer mechanism. Figure 19 is a fragmentary vertical transverse section taken on line 19—19, Figure 18. Figure 20 is a vertical longitudinal section taken on line 20—20, Figure 18. Figure 21 is a fragmentary horizontal longitudinal section taken on line 21—21, Figure 20. Figure 22 is a vertical transverse section taken on line 22—22, Figure 21. Figure 23 is a fragmentary rear elevation on an enlarged scale, showing the relation of the operating levers of the corresponding pulling jaw and gripping jaw which engage with one side of the head and shank of the spike for holding it in position while the same is being formed and while being carried toward and from the forming mechanism. Figure 24 is a fragmentary front elevation of the machine showing the manner of mounting the dies so as to permit them to yield under excessive pressure. Figure 25 is a vertical section on line 25—25 Fig. 12.

In the following description, corresponding characters of reference indicate like parts in the several figures.

The spike blank upon which my improved forming machine is adapted to operate, comprises a longitudinal shank 30 which is preferably square in cross section and provided at its upper or rear end with an enlarged head 31, and a blunt or square front or lower end 32, said head being of the usual oval form when viewed from the top, and offset relatively to the shank or body of the spike so as to form a comparatively wide shoulder 33 on the underside of this head on one side of the spike, and a comparatively narrow shoulder 33 underneath the opposite side of the head and adjacent to the side of the spike shank, as shown in Figures 5, 6, 7, 12, 13, 20 and 21. The transversely opposite edges also overhang the opposite lateral sides of the shank so as to form forwardly facing shoulder 34 thereon, as shown in Figure 21.

My invention is intended to produce one or more longitudinal grooves in one or more of the sides of the shank of this spike and to produce a point at the lower or front end of the same. In the preferred form of this machine, a longitudinal groove 35 is produced in each of the four sides of the shank, and at its lower front end, each of these sides is inclined, as shown at 36, so that these several inclined sides converge downwardly and produce a point or chisel edge 37 on the lower end of the spike. The bottom of each of the grooves 35 may either be plain or this surface may be provided with a plurality of longitudinal corrugations 38 as shown in Figures 7 and 9. A spike of this form, when driven into a tie, will not cut or crush the fibers of the same to such an extent as an ordinary spike, and owing to the greatly increased surface contact which is produced by the shank of the spike, due to the grooves of the sides of the shank, which is still further increased by corrugating the bottoms of these grooves, a much stronger hold of the spike upon the tie is obtained and the rails are therefore more securely and reliably fastened to the ties by the use of such spikes.

In its general organization, my improved forming machine, whereby the shanks of the spikes are provided with the grooves, either plain or corrugated as above described, and with pointed front ends, comprises a supplying mechanism which operates to supply blanks of the spikes which are to be grooved and pointed, a forming, forging, kneading or swaging mechanism whereby the shanks of the spikes are operated upon to produce either plain or corrugated grooves therein and also pointed ends thereon, and a feeding or transfer mechanism whereby the spike blanks are taken, one at a

time, from the supplying mechanism and presented to the forming mechanism and also discharged after the grooving and pointing operations have been completed.

The several working parts of this machine are mounted in a stationary main frame 39 which may be of any suitable construction, the forming mechanism being arranged on the front part of this machine, the spike blank supplying means being mounted on the rear part thereof and the feeding mechanism being arranged on the central part of the same.

Although the forming mechanism may be variously constructed so far as its details are concerned, and the same may also be organized to produce one or more longitudinal grooves and pointing surfaces on one or more sides of the spike shank, the particular arrangement of the mechanism which is shown in Figures 1, 4, 16 and 17 is designed to simultaneously forge the four longitudinal sides of a spike shank for the purpose of producing longitudinal grooves and inclined pointing faces thereon. For this purpose four forming dies 40 are arranged in an annular row around a forming space located at the front part of the machine, and each die being actuated so as to partake of both a radial motion toward and from forming space and also partake of a rocking motion in a direction lengthwise of the machine. Each of these dies is provided on the rear part of its inner side with a convex groove forming face 41 and on the front part of its inner side with an inclined forming face 42. The convex face is preferably of substantially semicircular form in cross section, as shown in Figure 11, and this face is also provided with longitudinal corrugations 43, as shown in the same figure so that when this face engages with a side of the spike shank, the latter will not only be indented so as to form a longitudinal groove therein, but the bottom of this groove will be formed with corrugations 38 corresponding to the corrugations of the rear groove face of the respective dies. The front or pointing face 42 of the die is flat so that upon engaging the same with the side of the spike blank, a corresponding flat finish will be produced on the spike blank, which flat finish is located at the front or lower end of the spike.

These several dies are actuated a plurality of times for the purpose of engaging the several sides of the spike shank progressively by the convex groove forming faces of the dies for the purpose of producing longitudinal grooves in the spike blank, and at the end of each series of groove forming operations of the die, the latter are so actuated that the flat point forming faces of the dies are engaged with the spike blank and form inclined impressions thereon,

which several inclined impressions or swaging operations together produce the pointed lower or front end of the spike.

Inasmuch as the mechanism for operating 5 the several dies to accomplish the above purpose is alike, the following description of the mechanism for actuating one of these dies will apply to all of them:

44 represents a stationary arbor which is 10 arranged transversely relatively to the length of the machine and mounted on the main frame in a manner which will presently appear. The center part of this arbor is of cylindrical form so as to provide a bearing 15 for an eccentric 45 which turns thereon. At one end, this eccentric has secured thereto, a forwardly projecting arm 46 which is adapted to be actuated by a cam 47, which is secured to an operating shaft 48 arranged 20 parallel with the arbor 44, said arm 46 being preferably provided with an anti-friction roller 49 for engagement with the cam 47 in order to reduce wear. Surrounding the eccentric 45 is an eccentric strap 50 to the 25 inner side of which, one of the dies 40 is detachably secured by means of bolts 51 or other suitable means. Projecting forwardly from the front side of this eccentric strap is a cam arm 52 which is adapted to be actuated by a cam 53, also secured to the shaft 48, this arm 52 being provided with a roller 54 for engagement with the cam 53 in order to reduce friction. The cam arm 52 is turned outwardly for the purpose of holding 35 the roller 54 yieldingly in engagement with the cam 53 by means of a longitudinal tension rod 55 connected at its rear end with a hook 56 on the inner part of the eccentric strap, a washer 56 held in place on the 40 front end of the tension rod by means of a screw nut 57 and forming a shoulder thereon, and a spring 58 surrounding the tension rod 55 and bearing at its front end against the shoulder or washer 56, while its rear end 45 bears against a head 59 which forms part of the main frame of the machine. The cam arm 46 is similarly held with its roller 49 in engagement with the cam 47 by a tension rod 60 connected at its rear end with 50 the lower part of the cam arm 46, and a spring 61 surrounding the tension rod 60 and bearing at its rear end against the frame head 59 while its front end bears against a shoulder formed on the rod 60 by means of 55 a collar or washer 62, and held in place thereon by means of screw nuts 63. The cam 53 which will hereafter be referred to occasionally as the "eccentric strap arm" is provided with a plurality of short throw cam faces 64 which are arranged in an annular row around the periphery of this cam so as to cover about three-quarters of the same, and a long throw cam face 65 arranged between the front and rear ends of the series 60 of short throw cam faces. The cam 47 will 65 hereafter be referred to occasionally as the "eccentric cam" and also is provided with a plurality of short throw cam faces 66 which are arranged in an annular series extending about three-quarters around the periphery 70 of this cam, and a long throw cam face 67, arranged between the front and rear ends of the series of short throw cam faces 66. The short throw and long throw cam faces of both of the cams 47 and 53, are nearly 75 the same form and arranged substantially on correspondingly circumferential parts of these cams, the slight difference in construction of these cam faces, as appears in Figure 16, being intended to perform functions 80 which will be explained later on.

In the operation of the machine, each of the shafts 48 makes one complete rotation for producing the grooving or pointing operation of the respective dies 40 on one 85 side of the spike shank. At the beginning of the forging operation of each die, the rollers 49 and 50 associated with the eccentric and eccentric straps, engage with the periphery of the cams 47 and 53 immediately 90 in the rear of the long throw faces 67 and 65 of these cams, in which position the corresponding die 40 is moved laterally outward from the path of the spike blank and this die is also moved into its foremost position, 95 as represented in Figure 16. As the two cams are rotated in unison from the place of beginning, shown in Figure 16, in the direction of the arrow associated therewith, the first effect is an inward movement of 100 the eccentric arm 46 which is effected by the first short throw face of the eccentric cam 47 whereby the eccentric will be returned in the direction for moving the convex rear or grooving face of the corresponding die 105 110 115 120 125 130 of the eccentric arm 46 drops into the depression of the next following short throw face of this cam whereby the die is retracted from the spike blank and at the same time, the first depression of the series of short throw cam faces 64 on the cam 53 is presented to the roller 54, thereby permitting the spring 58 to rock the die forwardly relatively to the spike blank. At the end of this forward movement of the die, the same is again moved radially inward and caused to 125 impress its convex rear groove forming face into the side of the spike blank, and at the same time, this die receives a rearward rocking motion so that its convex grooving face 130 engages the spike blank with a rolling action

and thereby produces a section of the longitudinal groove in the spike blank. At the end of this rearward rocking action of the die, the same is again moved radially outward or away from the spike blank by engagement of the roller 49 with the low portion of the next following short throw cam face on the cam 47 and after the pressure of the die against the spike blank is thus relieved, the same is also rocked forwardly by engagement of the roller 54 on the eccentric strap arm with the low part of the next following short throw cam face. This operation of the die upon the shank of the spike blank is repeated upon engaging each pair of corresponding short throw cam faces with the rollers on the eccentric and eccentric strap arms. These repeated operations of the die on the spike blank produce a longitudinal groove 35 therein, the bottom of this groove conforming to the shape of the convex face of this die, which bottom in its finished state, resembles a succession of depressions 68 which are of concave form in the direction of the length of the spike blank, and have their crests 69 joining each other so that this surface resembles a succession of waves, as shown in Figure 8. In the form of the cams 47 and 53, six short throw cam faces are employed whereby a corresponding number of short throw forging operations are produced on the side of the spike blank for producing a groove in one side thereof from a predetermined place below the head thereof to a place short of the lower end thereof. When the die reaches the last part or lower end of the spike blank, both the long throw faces 65 and 67 of the two cams operate upon the rollers 54 and 49 of the eccentric strap and the eccentric so that the die is not only radially inward a greater extent by means of the eccentric, but the die is also rocked rearwardly a greater extent, whereby the flat inclined pointing face 42 of the die is moved inwardly and longitudinally rearward a greater extent so that upon engaging this pointing face with the extreme lower or rear end of the spike blank, an inclined face 36 will be formed thereon, and constitute one of the several inclined faces which together produce the point or tapering lower end on the spike, thereby completing the same. During the operation of thus engaging the several dies with a rearward rolling action, the spike blank is moved rearwardly with the dies but remains at rest while the dies are retracted from the spike blank and moved forwardly preparatory to effecting the next forging or forming operation thereon. For this purpose, a spike blank feeding mechanism is provided which will be presently described and which operates to progressively feed the spike blank rearwardly intermittently in the same measure as the

operation of the forming dies proceeds, so that when the eccentric and the eccentric strap operating cams have completed each revolution, the operation of grooving the face side of a spike blank and forming the inclines thereon which together produce the point of the spike will also be completed. 70

The several arbors 44 are arranged at the front end of the machine so that together they form a square, two of these arbors being 75 arranged vertically and the remaining two being arranged horizontally. Each of these arbors is supported at its opposite ends on brackets 70 forming part of the front head 59 of the main frame, each of which brackets 80 is preferably provided with an outwardly turned face 71 which engages with an inwardly turned face 72 on the adjacent end of one of the arbors. For the purposes of enabling each of the dies to yield in case the 85 same encounters unusual resistance upon engaging the spike blank, means are provided for permitting each of the dies to yield under these conditions. This is preferably accomplished by yieldingly holding the opposite ends of each arbor 44 in engagement 90 with its respective brackets 70, and this is effected in the present instance by means of tension bolts 73 secured to the brackets 70 and passing through the opposite ends of the 95 arbor 44, and springs 74 surrounding each tension bolt and bearing at its inner end against the outer side of one end of the arbor 44, while its opposite end bears against the head of the bolt as best shown in Figure 24. 100 By thus enabling the dies to yield, breakage of parts of the machine or clogging of the same is avoided when a spike blank of excessive thickness or one of unusual hardness is presented to the forming mechanism. 105

The cam shafts 48 of the several pairs of cams are also arranged at the front end of the machine so that they together form a rectangular frame, two of these shafts being arranged vertically and the other two being 110 arranged horizontally. Each of these cam shafts is journaled in bearings 75 on the head 59 of the main frame and these shafts are caused to turn in unison by means of a pair of co-operating bevel gear wheels 76 115 mounted on the adjacent ends of the several cam shafts, as best shown in Figure 4.

The numeral 77 represents the main driving shaft of the machine which, in the present instance, is journaled horizontally and transversely in bearings 78 on the lower front part of the main frame. Motion is transmitted from this main driving shaft to the cam shafts by means which are preferably so constructed that the cams and associated parts will only be rotated while a spike blank is in the forging position between these dies and the latter are operating on this blank, and rotation of these cams is arrested during the time that the finished 125 130

spike is being carried away from the dies and another spike blank is being fed into the forging position between the dies. The position of the parts during the period of rest is indicated in Figure 16, which also represents the beginning and ending of the rotation of the cams for effecting a series of forging operations of the dies on the spike blank. To effect such intermittent rotation of the die operating cams, motion is transmitted from the main shaft 77 to the several cam shafts 48 by means of a large intermittent gear wheel 79 mounted on the main driving shaft 77 and meshing with an intermittent gear pinion 80 on the lower horizontal cam shaft 48, as shown in Figures 1 and 4.

It is essential that the spike blank be so positioned with reference to the forming or forging mechanism that when the flat inclined or pointing surfaces 42 of the several dies engage with the lower or foremost end of the spike blank, that the front extremity of this blank will terminate in line with the front ends of the flat faces 42 of the several dies. In order to thus insure moving the spike blank rearwardly during the last step of the forming operation thereon while the pointing faces 42 of the dies are engaging therewith, a blank placing device is provided which operates during the last part of the forging operation of the dies, to push the spike blank rearwardly, if this should be necessary, so that no part of the same will project forwardly beyond the dies as the latter perform the last or pointing operation on the spike blank. Although this may be accomplished in various ways, the means shown in the drawings for this purpose are preferred, and as there shown, the same are constructed as follows:

The numeral 81 represents a positioning rod which is guided in a way 82 on the front part of the frame head 59 so as to be capable of longitudinal horizontal movement relatively to the place where the spike blank is operated upon by the dies, and which is adapted to engage its rear end with the front end of any spike blank which may be located too far forward. A longitudinal reciprocating movement of this positioning rod is effected by means of an upright rocking lever 83 which is pivoted on the adjacent part of the main frame so as to swing in a vertical plane lengthwise of the machine and provided in its lower arm with a slot 84 which receives a pin 85 on the front end of the positioning rod 81, a rocking shifting arm 86 projecting upwardly from the eccentric strap and eccentric arm 52, and a shifting link 87 which produces a slack connection between the shifting arm 86 and the rock lever 83 and which is pivoted by means of a pin 88 to the upper arm of the rock lever 83 and provided

at its rear end with a slot 89, which receives a pin 90 on the upper end of the rocking shifting arm 86. During the rocking motion of the eccentric strap 50 which is imparted thereto by the series of short throw cam faces 64, the pin 90 of the shifting arm 86 moves idly back and forth in the slot 89 without disturbing the position of the positioning rod 81. During the last rearward rocking motion, however, of the die 40 for producing a pointing action on the front end of the spike blank during which time this die is rocked rearwardly to a greater extent than when the same is operated for producing a groove in the spike blank, such increased throw of the eccentric strap at this time also produces an increased forward throw of the shifting arm 86 which operates to move the positioning rod 81 rearwardly so that the rear end of the same is in line with the front ends of the dies 40 at the time the flat pointing faces 42 of these dies engage with the front end of the spike blank. If, therefore, a spike blank, while in its forging position, should be so located with reference to the dies that the front end of this spike blank would project forwardly beyond the dies while the latter effect their last operation, such abnormal projection of the spike blank forwardly beyond the dies is prevented by the action of the positioning rod which pushes the spike blank rearwardly at this time so that its front end is flush with the front ends of the dies 40 as the latter effect the last or pointing operation on the spikes. By this means, the formation of fins or remnants on the pointed ends of the finished spikes is avoided and insures finishing the spikes with perfect sharp points at the lower or front end of the shanks, which permits of effectively using the same without requiring any other operation for putting the same in shape for immediate use.

During the first forward stroke or rocking movement of the respective die 40 which is associated with the shifting arm 86, after this die has effected a pointing operation on the spike blank, the pin 90 of the shifting arm engages with the rear end of the slot 89 in the shifting link 87, thereby causing the positioning rod 81 to be again drawn forwardly into its foremost position out of the path of the spike blank which is moved into the forging place, preparatory to being again moved rearwardly and positioning any spike blank which may be too long and thus causing the same to be pointed by the die without an objectionable fin or remnant thereon.

The mechanism for feeding the spike blanks from the supplying means to the forging means and moving the blanks rearwardly intermittently relatively to the forming means during the operation of

forging the grooves and points thereon is constructed as follows:

- The supplying means are so constructed that they present the spike blanks successively to a position where the same are taken by the feeding mechanism from the supplying means and presented to the forming mechanism. The foremost spike in the order in which they are supplied by the 5 supplying means is represented in a vertical position at the right hand side of Figure 12 and while the same is in this position, it is grasped by the feeding mechanism and presented to the forming mechanism. 10 This feeding mechanism comprises a gripping device which is so constructed that it grasps opposite sides of the head of the spike which is at the upper end thereof and also the shank of the same at a point below 15 the head thereof, means for rocking this gripping device vertically for the purpose of carrying the spike from a pendent position, shown in Figure 12, to a horizontal position shown in Figure 20, and means for 20 moving the spike lengthwise relative to the forming mechanism while the spike is in a horizontal position. 25

This gripper mechanism is mounted on the front end of a horizontally movable slide 91 which is guided in suitable ways 92, on the upper rear part of the main frame and is provided on its rear part with a gap 93, within which part of the spike supplying mechanism is arranged. Pivots mounted 30 on the front end of the slide 91 so as to be capable of swinging vertically thereon, is a yoke 94, this pivotal connection being preferably effected by means of a shaft 95 which is journaled in suitable bearing 96 on the front end of the slide 91 and upon the central part of which the upper end of the yoke 94 turns.

When this slide is in its rearmost position, the yoke 94 projects downwardly from this slide, as shown in Figure 12, but when this slide is in its forward position and presenting a spike blank to the forming means, the yoke is in a horizontally forward projecting position relatively to the slide, as shown in 45 Figure 20. Means are provided which tend constantly to move the yoke 94 from its horizontal position, shown in Figure 20, to its vertical pendent position shown in Figure 12, which means preferably consist of a sleeve 97 surrounding one end of the shaft 95, having its inner end secured to the yoke 94 and journaled in a bearing 98 at the front end of the slide 91, and a spring 99 surrounding the sleeve 97 and secured at one 50 end to the slide 91, while its opposite end is secured to a collar 100 at the outer end of the sleeve 97 as best shown in Figures 18 and 19. Projecting rearwardly from the inner end of the yoke 94 is a controlling arm 101 which is provided with a curved cam

surface 102 at its inner end adjacent to the shaft 95 and a straight surface 103 at its outer extremity. This controlling arm engages with the under side of abutment 104 which is preferably constructed in the form 70 of a roller mounted on a stationary axis 105, which preferably consists of a rod mounted on the adjacent part of the main frame of the machine.

As the slide 91 effects the last part of its 75 rearward motion, the curved receding part 102 of the controlling arm presses underneath the abutment 104, thereby permitting the spring 99 to turn the yoke 94 from the horizontal forwardly projecting position on the slide 91, as shown in Figures 18 and 20, to the pendent position shown in Figure 12. When, however, the slide 91 is moved into its forward position relatively to the forming mechanism, the abutment 104 engages 80 with the horizontal upper side of the outer part of the controlling arm and causes the yoke 94 to be shifted from the pendent position shown in Figure 12 to the horizontal forwardly projecting position shown in Figures 18 and 20, which last mentioned position causes the spike blank to be held 85 in a horizontal longitudinal position with its head rearmost, in which position it is moved forwardly to its foremost position 90 between the several dies and then retained in this position while being moved rearwardly, step by step, for performing the several forging operations thereon, after which the yoke is again swung downwardly into a 95 pendent position, during which last movement the finished spike is first discharged from the gripping mechanism mounted on the yoke and this gripper mechanism is then engaged with another spike blank preparatory to beginning another cycle of operations.

Means are provided for limiting the rearward and downward swinging movement of the yoke 94 under the action of the spring 110 99, which means serve to arrest the motion of this yoke when the same reaches a vertical position, and although these limiting means may be variously constructed, those shown in the drawings are preferred, and consist of a stop pin 106 secured to the rear side of the sleeve 97 and working in a slot 107, in the bearing 98, the upper end 108 of this slot serving as a stop which is engaged by the stop pin 106 when the yoke swings 115 downwardly and rearwardly into its vertical lower position, as best shown in Figures 18, 19, and 20.

The gripping means which are adapted 125 to grasp the spike blank and support the same on the yoke as the latter moves from its vertical lower position to its horizontal upper position, and while the spike is being moved toward and from the forming mech-

anism, preferably comprises two pairs of jaws, a front pair 109, 109, which are adapted to engage transversely opposite sides of the shank of the spike immediately in front of its head and which will be hereafter referred to as the "shank jaws", and a rear pair of jaws, 110, 110, which are adapted to engage with transversely opposite sides of the edge of the spike head and which will be hereafter referred to as the "head jaws". The face of each shank jaw is provided with a flat bottom 111 and two inclined sides 112, so that when the two head jaws are moved toward each other and into engagement with opposite sides of the spike shank, the latter will be centered on the concave faces or recesses of these jaws and reliably held in definite and pre-determined position thereby. The face of each head jaw is provided with a straight face 113 which is adapted to engage with the peripheral edge of the spike head on one side thereof, and an inwardly projecting flange 114 arranged at the front end of each of the head jaws and adapted to engage underneath the adjacent part of the head of the spike, the inner or rear edge of each head jaw being unflanged, thereby compelling the spike blank, when engaged by the head jaws, to move rearwardly therewith, by permitting the spike blank, under certain conditions, to be moved rearwardly independently of these head jaws, as will be explained later on.

The two head jaws of the gripper mechanism arranged at the outer or lower end of the rocking yoke or carrier 94 are secured to the lower or rear ends of a pair of hollow parallel outer shafts 115 which are journaled lengthwise in parallel bearings 116 formed on the yoke 94. Secured to the upper or rear ends of the hollow shafts 115 are two head operating rock levers, the inner arms 117 of which project downwardly and rearwardly over the rear part of the shaft 95, while the upper arms 118 of these rock levers project upwardly from the hollow shafts 115. A rotary cam 119 is mounted upon the shaft 95 and provided with cam surfaces on its opposite sides and between the upper arms 118 of these rock levers, an expansion spring 120 is arranged. When the cam 119, during its rotation with the shaft 95, presents the high parts of its cam surfaces to the lower arms 117 of the head jaw levers, the latter will be turned in the direction for operating the lower arms 117, and also operating the head gripping jaws 110 so that they are moved away from opposite sides of the position in which they would grasp the head of the spike blank. During movement, the spring 120 between the upper arms of the head jaw levers, is compressed, and when the cam 119 presents its low faces to the lower arms of the head jaw levers 117, the latter are moved toward each other by the spring 120 and the head gripping jaws 110 are simultaneously moved toward each other and engaged with opposite sides of the head of the spike blank while the gripping mechanism is in the position for receiving a spike blank from the spike blank supplying mechanism. Journaled within the hollow outer shafts 115 are two inner shafts 121, each of which has secured to its lower or front end one of the shank gripping jaws 109, and each of which has secured to its upper or rear end, a shank jaw lever, the lower arm 122 of which is provided with an inwardly facing shoulder 123, which is adapted to engage with the adjacent part of the outer side of the companion lower arm of the respective hollow shaft 115. The shoulder 123 of the lower arms 122 is yieldingly held in engagement with the lower arms 117 by means of a spring 124 interposed between the upper arms 125 of the shank jaw levers.

During the last part of the rearward motion of the slide 91, the gripper yoke 94 swings forwardly and downwardly into a vertical position and brings its two pairs of jaws 109 and 110 on opposite sides of the shank and head of the foremost spike blank of the spike blank supplying mechanism, but at this time these jaws are in a separated or open position so that they will clear the respective spike blank. Upon, however, reaching this rearmost position, the operation of the cam 119 will permit the springs 120 and 124 to move the gripper jaws 109 and 110 into a closed position against opposite sides of the shank and head of the spike blank and obtain a firm grip thereon so that during the subsequent forward and upward swinging movement of the carrying yoke 94, the spike blank will be carried from the blank supplying means in which it assumes a pendent position upwardly and forwardly into a horizontal position in which it projects with its front end forwardly relatively to the center of the spike forming mechanism. After the spike blank has been thus raised into a horizontal forwardly projecting position by the upward swinging movement of the yoke 94 on the slide 91, the latter is moved forwardly preferably by one continuous movement until those portions of the several sides of the spike shank immediately below or in front of the shank jaws 109 are in line transversely with the convex rear faces of the forming dies 40. When the blank reaches this position, the forming mechanism begins to operate upon the shank of the spike blank in the manner previously described during which time the spike blank is fed backward intermittently, and the convex or groove forming portions of these dies operate successively and step by step upon

the spike blank for producing the longitudinal grooves therein, and when the last or lowermost or front end portion of the spike blank has reached the flat or point forming faces of the dies, the positioning rod 81 moves rearwardly and operates to push the spike blank rearwardly, if the same is of excessive length, and insures bringing the lower or front end of the spike blank in line 10 with the front end of the dies so that the point forming portions of these dies will be able to produce a finished or clean cut point on the spike blank without leaving any fin or remnant of metal thereon, previously 15 explained in greater detail. If a spike blank should be pushed rearwardly by the positioning rod 81 during the last part of the forming operation on the spike blank, the shank of the spike blank will simply 20 slip through the shank jaws 109 of the gripper mechanism and the head of the spike blank will move a corresponding extent rearwardly relatively to the opposing faces of the head jaws 110 and away from the 25 flanges 114 thereof, without, however, disturbing the hold otherwise of the gripping mechanism on the spike blank. During the rearward movement of the gripping mechanism, while the spike blank is being engaged 30 by the forming dies, this blank is compelled to move with the gripper mechanism owing to the engagement of the front flanges 114 of the head jaws 110 with the under side of this head which, at this time, faces forwardly or toward the forming mechanism. 35

The relative position of the lower arms of the jaw and head gripper levers is such that when the cam 119 is turned in the position in which it permits these arms to move toward each other, the movement of the lower arms 122 of the jaw levers will be arrested first by the engagement or closing of the gripper jaws 109 with the opposite sides of the shank of the spike blank, and thereafter, the lower arms 117 of the levers associated with the head gripping jaws are permitted to move toward each other independently of the lower shank jaw arms 122, until the two head jaws 110 also engage 40 with opposite sides of the head of the spike blank. When, however, the high parts of the cam faces of the rotary cam 119 engage with the lower arms 117 of the head gripping levers, the latter effect the initial part 45 of their operating movement independently of the lower arm 122 of the shank gripping levers, but during the last part of the operating movement of the arms 117, the same engage with the shoulder 123 of the arms 50 122 so as to compel the shank gripping levers to move therewith. As a result of this, the head gripping jaws of the gripper mechanism are opened or disengaged first 55 from the head of the spike blank and the jaws of the shank gripping lever are opened 60 or disengaged from the shank of the spike blank last. By this means, the spike hold is always gripped first at its shank before its head is engaged, and this hold on the shank is retained until after the head is released, thereby insuring holding the spike blank reliably in its centered position at all times from the time that it is gripped at the outlet of the spike blank supplying mechanism through the time that the spike blank 70 is moved toward and from the forming mechanism and up to the time that the finished spike is discharged from the gripper mechanism. Such discharge of the finished spike occurs immediately after the finished spike has been moved rearwardly from the forming mechanism and the gripper mechanism is effecting the first portion of its downward and rearward motion, at which time the cam 119 opens the two pairs of jaws 80 and releases the grip on the finished spike and permits the same to fall into a delivery chute 125 which receives the finished spike and delivers the same laterally from the machine upon the floor of the building or into 85 a receptacle provided for that purpose. 90

The longitudinal forward and backward movement of the slide 91 may be effected by various means, preferably those shown in the drawings, which are constructed as follows: 95

The numeral 126 represents an upright rock lever which is pivoted at its lower end by means of a horizontal transverse pin 127 so that the same swings in a vertical 100 plane lengthwise of the machine. The upper part of this rock lever is forked and each of its tines or arms 128 has pivotally mounted on its front end, a sleeve 129 which is mounted on a horizontal shifting rod 130 105 arranged lengthwise in the upper part of the machine. Each of these shifting rods is pivotally connected at its front end by means of a pintle 131 with the front part of the slide 91, and at a distance in front of the sleeve 129 thereon, the same is provided 110 with a collar 132. Surrounding the shifting rod 130 between the lever sleeve 129 and the collar 132, is a spacing sleeve 133, whereby, upon moving the front end of the lever 126 forwardly, the movement of the same will be transmitted to both shifting rods 130 to the slide 91 and the parts mounted thereon. On the rear end of each of the shifting rods 130 is mounted a stop collar 120 or shoulder 134 and upon these rods are mounted springs 135, each of which engages its front end with the rear side of the lever sleeve 129, while its rear end engages with the front side of the respective collar 134. These springs 135 are sufficiently stiff so that during ordinary conditions, the lever or coupling sleeves 129 will be maintained in a definite position on the shifting rods 130. If, however, during the 125 130

rearward movement of the slide 91, the spike blank, which is being operated upon, should become stuck in the forming or forging apparatus or if anything else should happen to the parts associated with the slide, to prevent free rearward movement thereof, then the shifting lever 126, during its rearward movement, will simply compress the springs 135 until the clogged condition in the machine is removed, thereby avoiding breaking any of the parts.

The rearward motion of the shifting lever 126, while the forging or forming operations on this spike blank are being performed, is accomplished by positively operating means, but the forward movement of this lever is effected by spring means. These means, in the preferred form shown in the drawings, are, as shown in Figures 1 and 4, constructed as follows:

The numeral 136 is a cam secured to the driving shaft 77 and provided with a plurality of short throw cam faces 137, which are progressively higher or farther away from the center of rotation of this cam, and a long throw cam face 138 which extends from the lowest to the highest of the series of short throw cam faces 137. The effect of this cam 136 is transmitted to the shifting rock lever 126 by means of a pitman or connecting member which, in the preferred construction, comprises a front head 139, having a roller 140 arranged to be engaged by the long and short throw cam faces on the periphery of the cam 136, a rear coupling head 141 connected with the lower part of the shifting lever 126 and an intermediate adjusting rod 142, having right and left hand screw connections 143, 144 with the front and rear coupling heads 139, 141. As the cam 136 turns and presents its successively higher short throw cam faces 137 to the lower 140, the pitman will be pushed rearwardly together with the shifting lever 126, and cause the gripper mechanism to be moved rearwardly, step by step, from the forming mechanism to the spike blank supplying mechanism, and when the long throw 138 of the cam 136 engages with the lower 140, the pitman is moved forwardly by the spring return device, together with the shifting lever 126, the slide 91 and the gripper mechanism for the purpose of carrying a spike blank by means of the gripper mechanism from the spike blank supplying device to the forming mechanism. This spring return device in the present instance consists of a return spring 145 surrounding the central part of the adjusting rod 142 and bearing at its front end against the collar 146 on the rod 142, and at its rear end against a shoulder 147 on the main frame. By turning the adjusting rod 142 in one direction or the other, the shifting lever 126, together with the slide 91 and the gripper mecha-

nism carried thereby may be adjusted lengthwise of the machine for the purpose of causing the gripper mechanism to present the spike blank properly to the forming mechanism. Such turning of the adjusting rod 142 may be readily effected while the machine is in operation by turning this rod through the medium of a hand wheel 148 secured to the rear end of this rod, as shown in Figure 1.

Due to the right and left hand screw connections between the adjusting rod 142 and the front and rear coupling heads 139 and 141, a turning of this screw rod in one direction will cause the pitman as a whole to be shortened and the gripper mechanism to be moved forwardly relatively to the forming mechanism while a turning movement of the rod 142 in the opposite direction will cause the gripper mechanism to be moved rearwardly relatively to the forming mechanism. During the longitudinal movement of the pitman, the front end of the same is guided on the hub 149 of the cam 136 by constructing the front end of the coupling head 139 in the form of a fork 150 which straddles the hub 149, as shown in Figures 1 and 4. For the purpose of enabling the stroke of the gripper mechanism lengthwise of the machine to be adjusted so as to adapt the same to variations in the length of the spike blank, means are provided which, in their preferred form, consist of a vertically movable clamping screw 151 mounted on the rear coupling head 141 and passing through an upright slot 152 in the lower part of the shifting lever 126. By loosening the adjusting screw 151 and raising the same in the slot 152, the length of the arc through which the lever 126 swings, will be reduced and thereby produce a corresponding reduction in the length of the longitudinal stroke of the slide 91 and the gripper mechanism mounted thereon, while upon lowering this adjusting screw in said slot, the arc through which this lever moves will be increased and thereby produce a correspondingly longer stroke of the gripper mechanism lengthwise of the machine. After such adjustment is effected, the adjusting screw 151 is tightened so as to hold these parts in their adjusted position.

Means are provided for transmitting motion to the shaft 95 without interfering with its free longitudinal movement in the machine as the gripper mechanism moves back and forth between the spike blank supplying means and the forming means. The preferred form of driving mechanism for this gripper shaft 95, as shown in the drawings, is constructed as follows:

The numeral 153 represents a short counter shaft journaled transversely and horizontally in a bearing on one of the longitudinal walls of the frame and provided on

the outer side of this frame with a sprocket pinion 154, and on the inner side of the frame with a bevel gear wheel 155. Rotary motion is imparted to this counter shaft 153 by means of a chain belt 156 passing with its front turn around a large sprocket wheel 157 on the main driving shaft 77, and passing with its opposite turn around the small sprocket wheel 154. An extensible shaft is provided as part of the means for transmitting motion from the shaft 153 to the shaft 95, which shaft comprises upper and lower end sections 158 and 159 and an intermediate section 160, which is of hollow form and receives the end sections 158 and 159, and is connected therewith so as to be capable of operating lengthwise thereon but compelled to turn therewith each of these connections preferably consisting of a pin 161 secured to one of the end shaft sections and passing through a slot 162 on the intermediate shaft section 160, as shown in Figures 1 and 19. The upper end section 158 of the extensible shaft turns in a bearing 163 formed between a swiveling bracket 164 which turns on the adjacent end of the shaft 95, and a lower section 159 of the extensible intermediate shaft is similarly connected by means of a similar swiveling bracket 165 which has a bearing for the lower shaft section 159 and also turns on the counter shaft 153. The lower shaft section 159 is provided with a bevel gear wheel 166 which meshes with the bevel gear wheel 155 on the counter shaft, and the upper shaft section 156 is connected with the adjacent end of the gripper shaft 95 by a pair of intermeshing bevel gear wheels 167.

By means of this construction, the gripper is free to move lengthwise in the machine and still preserve the driving connection of the shaft 95 with the counter shaft 155 during which time the extensible shaft will lengthen while the gripper is moved forwardly in the machine and shorten while the gripper is moved rearwardly therein.

Means for supplying the spike blanks to the feeding mechanism are constructed as follows:

Arranged lengthwise in the upper rear part of the main frame of the machine is a runway upon which the spike blanks are deposited by any suitable means, and whereby the same are directed forwardly to the outlet of the runway where they are taken by the gripping device of the feeding mechanism, preparatory to being presented to the forming mechanism. In its preferred form, this runway consists of two longitudinal rails 168 which are arranged in an inclined position within the slot 19 in the feeding slide 91 and between the shifting rods 130 of the same so that these rails slope downwardly from their elevated rear ends to their depressed front or discharge ends. These rails are separated from each other so as to form a longitudinal slot 169 between the same, and they are held rigidly in position on the main frame by providing them with laterally projecting lugs 170, which are secured to the main frame by means of screws 171, as best shown in Figures 3 and 12. The space between the rails of the runway is slightly greater than the width of the shanks of the spikes so that the latter are free to slide forwardly in this slot, but the same are held against turning therein and thereby insure proper presentation of the spike blanks to the feeding mechanism at the outlet of the runway. The heads of the spikes, however, are adapted to overhang with their lateral edges over the top surfaces or guideways 172 formed by the upper sides of the guide rails and thereby serve to suspend the spikes on the runway as they slide from the rear to the front end thereof. When the machine is in operation, a plurality of spike blanks are arranged in a longitudinal row on this runway, one behind the other, with their shanks projecting downwardly in the slot between the guide rails and their heads resting on top of these rails, and the rear or long part of the head of each spike blank projecting rearwardly and engaging the front side of the next following spike blank immediately below the head of the latter, as illustrated in Figure 12. The foremost spike blank of the row on the runway is arrested and prevented from escaping from the runway preparatory to being engaged by the gripping device of the feeding mechanism, while the rear part of the under side of the head of this foremost spike blank rests upon the front or discharge ends of the rails 168, which front ends are preferably turned or curved upwardly somewhat in the form of short horns or fingers 173, as shown in Figure 12. As each spike, while in its foremost position in the row on the runway, is carried away by the gripper mechanism, the remaining spike blanks or supply row on the runway, slide by gravity forwardly one space so that they are all advanced in one step and the next spike blank, which is now foremost, will take its place on the front ends of the rails ready to be grasped by the gripping device of the feeding mechanism. After each foremost spike blank has slid forwardly on the front ends or horns 173 of the guide rails so that only the rear parts of its head rest on these horns, the further forward movement of this spike blank is arrested by a detent device or gate mechanism which extends across the path of the spike blanks at the front or outlet end of the runway and retains the foremost spike blank in the delivery position on the runway while the previously removed spike blank is being carried away by the gripper and presented to the forming mechanism. In the pre-

ferred construction of this detent mechanism, the same comprises a vertical swinging detent arm 174 which has its axis of rotation arranged at the front end of the runway, but above the path of the heads of the spike blanks, while its lower end is provided with a rearwardly projecting detent finger 175 which is adapted to engage with the front side of the foremost spike blank on the runway at the corner between its head and shank and thereby prevent this blank from sliding off the runway until after the spike blank has been grasped by the gripping device and the detent arm and finger have been moved forwardly and upwardly so as to clear the path of the head of the spike blank and allow the gripping device to move the blank forwardly to the forming mechanism. The upper end of the detent arm 174 is mounted on a horizontal transverse rock shaft 176 which is journaled in a normally stationary bearing 177 and this shaft is yieldingly turned in the direction for moving the detent arm 174 and its finger 175 downwardly and rearwardly by means of a spring 178 surrounding the shaft 176 and connected at its opposite ends with said shaft and an adjacent part of the carrier 179 on the front end of which the bearing 177 is arranged. The downward and rearward swinging motion of the detent arm and finger under the action of the spring 178 is limited by means of a stop device which, in its preferred form, consists of a pin 180 mounted on a collar 181 secured to the shaft 176 and adapted to bear against a shoulder 182 formed on the adjacent part of the carrier 179, as best shown in Figures 12, 14 and 15.

When the gripper is moved forwardly relatively to the runway of the supplying means and not in operative relation thereto, the spring 178 holds the detent arm and finger in its operative relation across the top of the spike blanks at the outlet end of the runway so that the finger of this detent mechanism will be engaged by the front edge of the head of the foremost spike blank and the latter will be arrested in its forward movement, as shown in Figure 12. When, however, the gripping device has grasped the foremost spike blank and the latter is being carried forwardly away from the supply of spike blanks, the detent arm and finger are swung forwardly and upwardly by the action of the head of the spike blank which is being carried away, and during this time, the next following spike blank of the row on the supplying means is engaged by a detaining wing or segment 183 which projects upwardly from the detent arm 174, by swinging downwardly whenever the detent arm 174 swings upwardly, thereby causing the detaining wing 183 to engage with the front edge of the head of the next follow-

ing spike blank for the purpose of preventing the latter from sliding forwardly at this time while the preceding spike blank is being carried away by the gripper and the outlet of the spike blank runway is unobstructed. The instant, however, that the detent arm 174 and its finger 175 are again swung downwardly into a position in which the detent finger 175 again stands in its operative position across the path of the spike blanks at the outlet of the runway, the detaining wing 183 has been again raised into a position in which it clears the head of the next following spike blank so that the latter is now free to slide downwardly by gravity and rest with the rear part of its head on the delivery horns 173 and engage with the front part of its head against the detent finger 175, as shown in Figure 12. The detent finger 175, the arm 174 and the detaining wing 183, therefore, operate as an escapement or gate mechanism which only permits one spike blank at a time to be delivered from the outlet end of the runway. The two sets of jaws of the gripper mechanism are so organized and timed that they cross upon the head and shank of the foremost spike of the row on the runway immediately after the previously finished spike has been discharged from the gripper mechanism and this engagement of these jaws occurs immediately after the yoke or rocking carrier 94 has moved downwardly and backwardly into a vertical position, as previously described. During the first part of the forward movement of this yoke or rocking carrier, after the gripping jaws have engaged the head and shank of the spike blank, the detent arm 174 and its finger are swung upwardly and forwardly out of the path of the head of the foremost spike blank so as to leave the gripper free to carry the same to the forming mechanism. This is preferably accomplished by means of a trip latch 184 pivotally mounted at its front end on the lower or front part of the yoke 94 so as to be capable of swinging vertically thereon, and provided at its rear end with a trip hook 185, adapted to engage with a trip lug 186 which projects downwardly from the hub 187 of the detent arm. The hook end of the trip latch 184 is yieldingly held in its elevated position by means of a spring 188 interposed between a shoulder 189 on the yoke 94 and a forwardly projecting tail 190 arranged on the trip latch 184, as best shown in Figures 12, 13, 15, 18 and 20. The upward movement of the trip latch under the action of the spring 188 is limited by means of a stop device which is preferably adjustable so as to permit of regulating the disengagement of the hook 185 from the trip lug 186. The adjustable stop device for this purpose, shown in the drawings, consists of a screw 191 arranged on the trip

latch 184 and adapted to engage with a stop surface 192 on the adjacent part of the yoke 94, as shown in Figures 12, 13 and 15. The distance from the axis of the shaft 176 to the outer end of the trip lug 186 is less than the distance from this axis to the end of the detent finger 175.

As the yoke 94 swings downwardly and rearwardly into its vertical position for bringing the gripping jaws in proper relation to the foremost spike blank for grasping the same, the trip latch 184 simultaneously trips with its hooked rear end 185 into engagement with the rear side of the trip lug 186. After the jaws of the gripping device have been closed upon the spike blank, the yoke 94 swings forwardly and upwardly in order to present the spike blank in a horizontal position lengthwise of the machine to the forming mechanism. During the first part of this upward and forward swing movement of the yoke 94 with the gripper mechanism, the hook 185 of the trip latch, by engaging with the trip lug 186, will cause the detent finger 175 to also swing upwardly and forwardly, but as the length of the trip lug 186 is shorter than the length of the detent arm and finger, the extent of the forward and upward swinging movement of the detent finger will be more rapid, thereby causing this detent finger 175 to promptly clear the path in advance of the forward and upward movement of the gripping device and enable the latter to carry the foremost spike blank away from the detent or escapement mechanism without interference from the latter. After the detent finger 175 has been raised sufficiently to clear the path of the head of the foremost spike blank, this detent finger continues to move in this direction until the hook of the trip latch slips off from the trip lug of the detent mechanism. This disengagement of the trip hook from the trip lug occurs immediately after the head of the foremost spike blank has passed forwardly beyond the detent finger 175, inasmuch as the gripper jaws and hook swing through an arc which has its axis concentric with the gripper shaft 95, and therefore has a radius of considerable length while the cooperating faces of the trip hook 185 and the trip lug 186 at this time swing through a small arc which has its axis on the detent shaft 176 and therefore has a comparatively short radius so that the hook 185 is simply stripped off from the trip lug 186 after these parts have moved together for a sufficient time to disengage the detent finger 175 from the head of the foremost spike blank, and has raised this finger a sufficient extent to avoid interference therewith of the head of the spike blank which is being fed at this time to the forming mechanism.

Inasmuch as each spike, upon reaching

the outlet or delivery position on the runway, is suspended only on the rear part of the under side of its head, the same, due to the overhanging weight, would not naturally assume a vertical or upright position but instead would incline rearwardly with the lower end of its shank. In order, therefore, to cause the spike blank to assume a vertical position when the same reaches the delivery place of the supply mechanism, and thereby insure grasping the same properly by the jaws of the gripper mechanism, a righting mechanism is provided which, in its preferred form, is constructed as follows:

The numeral 193 represents an upright righting arm or lever which is arranged along one side of the path of the spike blanks as they move forwardly in the runway and which is provided at its lower end with a laterally projecting finger 194 which is adapted to engage with the lower part of the rear side of the shank of each spike blank while the latter is in the delivery position and move the same forwardly so that the spike blank hangs vertically on the delivery end of the runway, as shown in Figure 12. This righting arm or lever is pivotally supported at its front end so as to be capable of swinging back and forth, this being preferably accomplished by providing the upper end of this arm with a hub 195 which turns on the exterior of the bearing 177 of the escapement shaft 176, as shown in Figure 14. This righting arm is swung backwardly so that its finger 194 is disengaged from the rear side of the shank of the spike blank in the delivery position and is arranged below the path of the lower end of the shank of the next following spike blank, as shown by dotted lines in Figure 12, so as to permit the next following spike blank to slide forwardly freely on the runway and take the place of the foremost spike blank at the delivery position. This rearward swinging movement of the righting arm is effected by means of a spring 196 interposed between a shifting arm 197 projecting upwardly from the righting arm and a shoulder 198 arranged on the adjacent part of the carrier 179, as shown in Figures 12, 14 and 15, the movement of the righting arm in this direction under the action of the spring 196 being limited by engagement of the arm 197 with a stop 199 on the adjacent part of the carrier 179, as shown in Figures 12 and 15. During the last part of the downward and backward motion of the yoke 94 which carries the gripper device, a shoulder 200 on this yoke engages with an adjusting screw 201 on the shifting arm 197 and causes the latter to be moved rearwardly in opposition to the spring 196, thereby causing the righting finger 194 to be moved forwardly into engagement with the lower part of the rear side of the shank

of the spike blank which is in the delivery position on the runway and causes this shank to assume a vertical position so that the same is capable of being properly grasped by the two pairs of jaws of the gripping device. As the gripping device is moved forwardly and carries the foremost spike blank with it, the shoulder 200 on the gripper yoke is moved away from the adjusting screw 201 and thereby permits the spring 196 to again turn the righting lever 193 so as to carry the righting finger 194 rearwardly below the path of the next following spike blank and enable the latter 15 to slide forwardly to take the place of the foremost spike at the delivery position.

When turning the adjusting screw or rod 142 for the purpose of adjusting the position of the ends of the stroke of the gripper mechanism to suit the length of the spike blank, which is being operated upon, it also becomes necessary to shift the place of delivery of the spike blank supplying means accordingly so that the spike blanks will be 25 located properly for engagement by the gripper mechanism. The required adjustment for this purpose in practice is very slight inasmuch as the spike blanks are substantially uniform in length, but, nevertheless, the spikes must be delivered to the gripper mechanism accurately in order to insure proper co-operation of the gripper mechanism therewith. This adjustment of the spike blank supplying means may be 30 effected by adjustably mounting the carrier 179 of the escapement mechanism on the main frame so that the detent lever 174, its finger 175 and the parts associated therewith, can be moved forwardly or backwardly relatively to the outlet of the runway and thus permit the head of the foremost spike blank to project a greater or lesser extent beyond the rails of the runway to suit the length of the spike and still permit the jaws of the gripping device to properly engage therewith. For this purpose, the carrier 179 is 40 constructed in the form of a longitudinal bar or plate which is frictionally secured to the under side of a horizontal guide surface 45 202 on the main frame and is frictionally held in engagement therewith by means of one or more tension bolts 203, each of which is secured with its upper end to the main frame and passes through a longitudinal slot 50 204 on the carrier 179, and a spring 205 surrounding the bolt 203 and bearing at its upper end through the medium of a washer 206 against the under side of the carrying bar 179, while its lower end bears against 55 a pair of screw nuts 207 on the lower end of the tension bolt 203, as best shown in Figures 1, 2, 3 and 12. By pushing the carrying bar 179 forwardly or backwardly, the detent finger 175 and associated parts can be moved 60 forwardly or backwardly relatively to the

outlet of the spike blank runway and thereby permit the foremost spike to extend or overhang more or less beyond the rails of the runway and thereby compensate for the changed terminus of the throw of the gripper mechanism which was made necessary to suit the length of the spike blank which is being operated upon.

Inasmuch as the adjustment of the escapement mechanism may be overlooked by the operator when changing from one length of spike to another, means are provided for the effecting of an adjustment of this compensating device automatically. These means, in their prescribed form, comprise two tappets which are adapted to be engaged by one of the arms of the shifting lever 126, a front tappet 208 which is secured to the rear part of the carrying bar 179 in position to be engaged by the respective arm of the shifting lever 126 during the last part of the forward stroke of the same, and a rear tappet 209 secured to the rear part of this carrying bar and adapted to be engaged by the same arm of the shifting lever 126 during the last part of the rearward stroke of this lever. The ordinary stroke after the machine has been once set for a certain length of spike will cause the shifting lever to rock through an arc which will cause the same, at the end of the stroke to engage with the front tappet 208 and at the rear end of this stroke to engage with the rear tappet 209, but not actually shift or disturb the position of these tappets nor the carrying bar 179 and the escapement mechanism mounted thereon, whereby the latter is normally left in a definite position where it is held in place frictionally by means of the tension of the springs 205. When, however, the adjusting screw rod 142 is turned for the purpose of adjusting the terminals of the stroke of the lever 126, to a new position to suit the length of the spike and cause the front or lower end of the same to be operated upon properly by the forming mechanism, the first forward stroke of the shifting lever 126 upon engaging the front tappet 208, will move the carrier 179 and the escapement mechanism forwardly slightly to an extent corresponding to the change which has been effected in the forward throw of this lever and the gripper mechanism, and thereafter this lever will again oscillate idly between the front tappet 208 and the rear tappet 209 without further changing the position of the escapement mechanism relative to the gripper mechanism.

After however, the adjusting screw rod 142 has been turned so as to throw the rearward terminus of the stroke of the shifting lever 126 back farther for producing a corresponding increase in the backward movement of the gripper mechanism to suit the length of the spike, then the shifting lever 130

126, at the end of its first rearward throw, will engage the rear tappet 209 and move the carrier 179 together with the escapement mechanism rearwardly to the same extent 5 corresponding to the changed location of the rearward terminus of the stroke of the gripper mechanism, and thereafter the shifting lever 126 will again oscillate idly between the front tappet 208 and the rear tappet 10 209 without further changing the relation of these parts until a further adjustment of the same is made necessary to suit the length of the spike blank which is being operated upon. It will, therefore, be apparent 15 that the shifting of the escapement mechanism so as to permit of varying the extent of overhang of the foremost spike blank on the runway and thus compensate for any variation in the length of the spike blank and harmonize the position of the spike blank at the delivery place for properly receiving mechanism, is effected automatically, without requiring any attention on the part of the operator for this purpose.

25 Whenever, therefore, the attendant notices that the finished spikes as they are discharged from the machine do not come out with their points in the proper shape, he simply turns the adjusting screw rod 142 30 one way or the other for changing the stopping places at opposite ends of the throw of the gripper and the spike blank carried thereby for bringing the blank into the desired position relatively to the dies, and the 35 escapement mechanism is automatically adjusted to conform to the changed throw of the gripper, this being accomplished while the machine is in operation and the operator is observing the product coming from the 40 machine. This compensating mechanism is intended to take care of spike blanks when one batch differs slightly in length from another, but when only an occasional spike blank is slightly of excess length, the automatically actuated positioning rod or plunger 81 is relied on to take care of the 45 same.

The operation of this machine, briefly, is as follows:

50 Assuming that the parts have been adjusted for operating on spike blanks of a certain length and that a supply of spike blanks has been placed on the runway chute, or magazine, the first effect upon starting 55 the machine is the closing of the gripper jaws on the head and shank of the foremost spike blank at the outlet of the spike blank supplying means. After the gripper jaws have taken hold of the spike blank, the latter 60 is swung upwardly and forwardly from a vertical to a horizontal position with the lower end of the shank facing forwardly. The gripper now moves forwardly and carries the spike blank into its foremost position in which the dies are nearest the head 65

of the same. The several dies now operate step by step with several sides of the spike shank and the blank at the same time is moved rearwardly step by step so that grooves, either plain or corrugated, are formed 70 lengthwise in the spike shank until the dies have nearly reached the front or lower end of the spike blank. Upon reaching the last mentioned part of the spike blank, the dies will be actuated so as to form a point on 75 the lower or front end thereof, whereupon the operation of the dies will cease and the same will remain at rest until another spike blank has been presented to the dies when the latter will resume their forging operation. After the finished spike has been withdrawn from the dies by the gripping mechanism, the jaws of the latter swing downwardly and rearwardly and during the first 80 part of this movement, the jaws of the gripping mechanism open to release the finished spike and remain open until the jaws are in line with the next following spike blank when the latter is grasped and the cycle of 85 operation just described is continuously 90 repeated so long as the machine is running.

I claim as my invention:

1. A machine of the character described, comprising a die having a convex face adapted to engage the shank of a spike, and means for moving said die bodily toward and from said shank and also rocking same in one direction while in engagement with said shank and in the opposite direction while out of engagement with said shank. 100

2. A machine of the character described, comprising a die adapted to work on the side of the shank of a spike, and means for moving said die toward said shank and also rocking the same while in engagement therewith, comprising an eccentric strap on one part of which said die is mounted and which is provided with a rock arm, a cam engaging said rock arm, an eccentric upon which said strap is mounted and which is provided with a rock arm, and a cam engaging the last mentioned rock arm. 110

3. A machine of the character described, comprising a die adapted to work on the side of the shank of a spike, and means for moving said die toward said shank and also rocking the same while in engagement therewith comprising an eccentric strap on one part of which said die is mounted and which is provided with a rock arm, a cam engaging said rock arm, an eccentric upon which said strap is mounted and which is provided with a rock arm, a cam engaging the last mentioned rock arm, and spring means for holding said rock arms yieldingly in engagement with said cams. 115 120 125

4. A machine of the character described, comprising a die adapted to work on the side of the shank of a spike, and means for moving said die toward said shank and also 130

rocking the same while in engagement therewith comprising an eccentric strap on one part of which said die is mounted and which is provided with a rock arm, a cam engaging 5 said rock arm, an eccentric upon which said strap is mounted and which is provided with a rock arm, a cam engaging the the last mentioned rock arm, and spring means for holding said rock arms yieldingly 10 in engagement with said cams, comprising a tension rod connected with each of said rock arms, and a spring bearing at one end against a shoulder on said tension rod and at its other end against a relatively stationary 15 abutment.

5. A machine of the character described, comprising a die adapted to work the side of the shank of a spike, an eccentric strap carrying said die and provided with a rock 20 arm, an eccentric upon which said strap is mounted and which is provided with a rock arm, cams engaging with said rock arms, and a yielding support for said eccentric.

6. A machine of the character described, 25 comprising a die adapted to work the side of the shank of a spike, an eccentric strap carrying said die and provided with a rock arm, an eccentric upon which said strap is mounted and which is provided with a rock 30 arm, cams engaging with said rock arms, and a yielding support for said eccentric, comprising an arbor, upon which said eccentric turns, brackets upon which opposite ends of said arbor rest, tension bolts passing 35 through said arbor and connected at one end with said brackets, and springs engaging with the ends of said arbor and with the heads at the other ends of said bolts.

7. A machine of the character described, 40 comprising a die having a front convex grooving face and a front flat pointing face, and means for actuating said die for engaging the grooving face thereof with the intermediate part of the side of a shank of the spike and the pointing face thereof with the end of the same.

8. A machine of the character described, 45 comprising a die having a front convex grooving face and a rear flat pointing face, and means for actuating said die for engaging the grooving face thereof with the intermediate part of the side of a shank of the spike and the pointing face thereof with the end of the same, comprising an eccentric 50 strap carrying said die and provided with a rock arm, an eccentric upon which said strap turns and which is provided with a rock arm, and rotary cams each engaging with one of said arms and each provided 55 with a plurality of relatively short throw parts and a long throw part, said short throw parts of said cams being adapted to move the die toward the intermediate part of said shank and simultaneously rock the 60 same moderately, and the long throwing 65

parts being adapted to move the die toward the end of said shank and simultaneously rock the same a greater extent.

9. A machine of the character described, comprising a die adapted to move toward 70 and from the side of the shank of a spike and provided with longitudinal corrugations for producing corresponding formation on the intermediate part of said shank, and a flat inclined face for producing a corresponding formation on the end of the shank. 75

10. A machine of the character described, comprising a die movable toward and from the side of the shank of a spike and also to rock relatively thereto, an eccentric strap 80 carrying said die and provided with a rock arm, an eccentric upon which said strap turns and which is provided with a rock arm, rotary cams for actuating said rock arms, a driving shaft, and means for transmitting motion from said driving shaft to said cams including a pair of co-operating intermittent gear wheels. 85

11. A machine of the character described, comprising a plurality of dies arranged in 90 an annular row around the place adapted to be occupied by a spike to be grooved, and means for moving said dies in unison toward and from said spike and also rocking the same relatively thereto, comprising rotary 95 cams for each die, a plurality of driven shafts mounted in rectangular relation to each other and each carrying the cams for one of said dies, intermeshing gear wheels arranged on the adjacent ends of the several 100 driven shafts, and a driving shaft operatively connected with said driven shafts. 100

12. A machine of the character described, comprising a forming device adapted to operate on the sides of the shank of a spike 105 blank, means for moving said blank relatively to said forming device, and a gage device adapted to operate on the front end of the spike blank and position the spike blank relatively to said forming device, said gage 110 device comprising a longitudinal movable gage pin adapted to engage the front end of the spike blank, and means for moving said gage pin toward the front end of the spike blank during the last part of the operation 115 of said forming device on said spike blank.

13. A machine of the character described, comprising a forming device adapted to operate on the sides of the shank of a spike 120 blank, means for moving said blank relatively to said forming device, and a gage device adapted to operate on the front end of the spike blank and position the spike blank relatively to said forming device, said gage 125 device comprising a longitudinal movable gage pin adapted to engage the front end of the spike blank, and means for moving said gage pin toward the front end of the spike blank during the last part of the operation 130 of said forming device on said

spike blank, comprising a rock-lever having one arm connected with said gage pin, a rocking member connected with another arm of said rock lever, and a cam for actuating said rocking member.

14. A machine of the character described, comprising a forming device adapted to operate on the sides of the shank of a spike blank, means for moving said blank relatively to said forming device, and a gage device adapted to operate on the front end of the spike blank and position the spike blank relatively to said forming device, said gage device comprising a longitudinal movable gage pin adapted to engage the front end of the spike blank, and means for moving said gage pin toward the front end of the spike blank during the last part of the operation of said forming device on said spike blank comprising a rock lever having one arm connected with said gage pin, a rocking member having a slack connection with another arm of said lever, and a cam for actuating said rocking member.

25 15. A machine of the character described,

comprising a die adapted to operate on the side of a spike blank, feeding means for moving the spike blank relatively to said die, a gage pin for positioning the spike blank 30 relatively to said die, and means for actuating said die and gage pin comprising an eccentric strap carrying said die and provided with a cam arm, a strap surrounding said eccentric and provided with a cam arm, 35 rotary cams engaging said cam arms, respectively, and each having a plurality of short throw faces which are adapted to move the die a number of times a moderate extent toward said spike blank and rock the same 40 moderately while in engagement therewith, and each cam also having a long throw face adapted to move said die a considerable extent toward said spike blank and also rock the same to a considerable extent while in 45 engagement with the end of the blank, a rock lever connected with said gage pin, a rock arm connected with strap, and a link forming a slack connection between said rock arm and rock lever.

FRED C. OLIN.
